MASSAGE ROLLER

Harley D. Niblack, Denver, Colo.

Application July 18, 1946, Serial No. 684,494

3 Claims. (Cl. 128—57)

1

This invention relates to a massaging device for reducing obesity, and has for its principal object the provision of a small, simple, neat, power-driven device for use in weight reduction parlors and the like, which will be very universal in its application to various portions of the human body.

Another object of the invention is to provide a massaging roller which will produce an alternating squeezing or pinching action on the flesh in combination with a rolling action for the reduction of fatty tissue.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawings:

Fig. 1 is a side view of the improved massaging device;

Fig. 2 is an end view thereof;

Fig. 3 is a longitudinal section, taken on the line 3—3, Fig. 2;

Fig. 4 is a cross-section, taken on the line 4—4, Fig. 3;

Fig. 5 is an enlarged detail view of an improved massaging roller employed in the device;

Fig. 6 is a longitudinal section through the improved roller, taken on the line 6—6, Fig. 5;

Fig. 7 is a cross-section through the roller, taken on the line 7—7, Fig. 6; and

Fig. 8 is a similar section, taken on the line 8—8, Fig. 6.

The improved massaging device is supported on two inverted, U-shaped frame members, preferably formed of metal tubing. The frame members consist of two vertical, downwardly-extending leg portions 10 joined by means of arcuate handle portions 11. The four leg portions 10 support a rectangular floor 12, from which two end plates 13 extend upwardly.

The end plates 13 are joined at the front and back of the device by means of front and rear panels 14. The upper extremities of the end plates 13 are rounded, and each carries a relatively narrow, arcuate guard plate 15, the lower extremities of which join the panels 14.

This provides an open space at the top of the device which exposes a plurality of massage rollers 16. The rollers 16 are mounted in, and extend between, circular roller plates 17, there being

2

one of the discs 17 adjacent each extremity of the opening in the top of the device.

The discs 17 are secured on a disc shaft 18 extending longitudinally of the device and are journaled in bearings 19 on the two end plates 13. The shaft 18 is rotated from a belt wheel 20 secured thereon. A driving belt 21 extends from the wheel 20 to a driving pulley 22 on a counter-shaft 23 journaled in supporting bearings 24 on the floor 12.

The counter-shaft 23 is driven from a speed reduction shaft 25 through the medium of a belt 26. The shaft 25 is driven from an electric motor 27 through the medium of a drive belt 28. The shaft 25 carries speed reduction pulleys 29 for the belts 26 and 28. The current to the motor 25 is controlled from a suitable control switch 30.

It can be readily seen that, when the motor 27 is operating, the discs 17 will carry the rollers 16 in parallel relation around the top of the device.

In use, the patient may sit upon the rollers 16, grasping the handles 11 in the two hands, or the patient may sit astride of the entire series of rollers, supporting himself by one the handles 11. For reduction of the calves of the legs, the patient may stand on one foot at the side of the device, allowing the calf of the other leg to rest upon the rollers. The unique construction of the device adapts itself to many other massaging uses.

The rollers may have any desired contour or configuration. It is preferred to form them as shown in detail in Figs. 5 to 8, inclusive. In these figures the rollers 16 are preferably turned from hard wood and the like, and terminate in rounded end flanges 31.

A plurality of diagonally placed rings 32 are placed intermediate the end flanges 31. The rings 32 are either formed on the rollers 16 or permanently secured thereto to form a single unitary roller. The rings 32 alternate in placement; that is, the first, third, and fifth rings incline inwardly in planes positioned substantially at 45° to the axis of the rollers 16. The intermediate rings, that is, the second, fourth, and sixth rings, incline outwardly at a similar angle.

When the roller is rolled against the flesh, the angular placement of the rollers produces a kneading or pinching action. For instance, the flesh between the first two rollers will be pinched gradually as the roller rotates 180°. The next 180° of rotation will result in a similar squeezing or pinching action between the next adjacent pair of rollers, the purpose being to break down the fatty tissues of the body for weight reduction purposes. The ends of the rollers are provided

with bearing sleeves 33 which ride upon bearing studs 34 projecting from the discs 17.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A massaging device for weight reduction comprising: two inverted, U-shaped frame members; a pair of vertical leg portions formed on said frame members; an arcuate intermediate handle portion formed on said frame members; supporting means secured to and extending between said frame members and supporting the latter in vertical, spaced-apart relation; end plates supported from said frame members at each extremity of said supporting means; a horizontal roller shaft extending between said end plates; a pair of spaced-apart roller discs secured to said shaft; a plurality of freely rotatable rollers extending between the peripheries of said discs in spaced-apart relation; panels extending between said end plates at each side of the device; an arcuate guide plate extending upwardly between the panels between each frame member and the adjacent roller plate; and means for rotating said shaft.

2. A massaging device for weight reduction comprising: two inverted, U-shaped frame members; a pair of vertical leg portions formed on said frame members; an arcuate intermediate

handle portion formed on said frame members; supporting means secured to and extending between said frame members and supporting the latter in vertical, spaced-apart relation; end plates supported from said frame members at each extremity of said supporting means; a horizontal roller shaft extending between said end plates; a plurality of freely rotatable rollers extending between the peripheries of said discs in spaced-apart relation; means for rotating said shaft; and a plurality of rings formed on said rollers in spaced relation and lying in planes inclined to the axis of the roller, the adjacent rings being inclined oppositely to each other.

3. A roller for massage devices comprising: a cylindrical roller; and a plurality of rings formed on and projecting above the cylindrical surface of said roller, the first, third, and fifth rings being inclined on a common angle to the axis of said roller, the second, fourth, and sixth rings being inclined on similar angle and in an opposite direction to the first rings, all of said rings being permanently affixed to said roller so as to rotate as a unit therewith.
